ERIC VINCENT MACKINTOSH, OF NEW MALDEN, AND CYRIL FRENCH, OF HAMPTON WICK, KINGSTON-ON-THAMES, ENGLAND.

DIAPHRAGM FOR TELEPHONE INSTRUMENTS.

Application filed August 13, 1926, Serial No. 129,015, and in Great Britain October 24, 1925.

This invention relates to improvements in diaphragms more particularly for use in loud-speakers and of the kind having an area many times greater than that of ear-
5 telephone diaphragms or those commonly used in horn-type loud-speakers and refers particularly to that class or type known as "large diaphragms" and which are clamped at their edges.

10 In order to describe clearly the nature of our invention we will state briefly what our experiments have led us to believe are the requirements for the type of diaphragm known as a "large diaphragm" for use in
15 a loud-speaker, the application of which is the object of this invention.

A diaphragm of this kind consists essentially of a surface which is employed as a medium for transferring the movements of
20 a vibratory member to the air, in the form of sound waves. The extent to which this is achieved is mainly dependent on the area, of such a surface, that can be made to follow the movements of the vibratory member.
25 This area, in the case of a diaphragm actuated at a single point, such as the centre, at any particular frequency, is, in turn, dependent upon the mass and rigidity of the diaphragm, and the manner in which it is mounted.

30 The effective area of a diaphragm may be increased, either or both, by reducing its mass or by increasing its rigidity, and this area will be greatest at the lowest frequencies.

35 The actual dimensions of a diaphragm required to respond to frequencies over the whole audible range will be governed mainly by the area which can be made to vibrate
40 effectively at the lowest frequencies, as there will be no advantage in exceeding this area, and any reduction of area will impair the efficiency of the diaphragm at the lower frequencies.

45 A diaphragm having a large effective area will be more or less damped according to the extent of this area, with consequent broadening of its natural resonance characteristic. Hence we find that increasing the
50 effective area not only increases the efficiency, but, by damping out natural resonance, the response throughout the whole range of frequencies is rendered more uniform.

In accordance, then, with our statement 55 that the volume efficiency and the evenness of response throughout the scale are both mainly determined by the effective area of a diaphragm, which is, in turn, dependent on the rigidity and mass of the diaphragm, 60 and the manner in which it is mounted, we have devised means for carrying these conditions into effect to the best advantage.

We employ a diaphragm of conical form and mount it by clamping it rigidly around 65 its edge, to provide a larger effective vibrating area than with a free edge diaphragm. We make the diaphragm of paper or like substance which we stiffen by reinforcing it with strips of material such as cane or bamboo applied to its surface.

70 It will be understood that by reinforcing a diaphragm in this manner a larger effective area of diaphragm can be obtained for a given mass of material than if a plain 75 sheet material only were used. We can make our diaphragms of a diameter as large as twelve inches, the whole area of which will be effective at the lowest frequencies, though the weight can be less than one ounce. 80

The natural period of this size of diaphragm is of the order of 60 vibrations per second which is sufficiently low to give effective response down to the limit of audibility.

85 The edge of the diaphragm may be held or clamped in any known or convenient manner, but in one form the edge is attached by glueing to an annular frame of some stiff material, such as Bristol board, of the same diameter as the diaphragm, which may form 90 part of the containing case, and will screen one side of the diaphragm from the other. The annular frame may be used without an external case and would then be made of sufficiently strong material. The diaphragm 95 is attached to the armature or driving means at its centre.

We will now describe our invention with reference to the accompanying drawing which is largely diagrammatic, with the case 100 a in section. The front of the case is open at b and may have therein an ornamental fret or equivalent as indicated by c.

105 The diaphragm 1 is of conical form and is connected at 2 to the reed or armature 3. The edge of the diaphragm is fixed at 1^a to a cylinder of cardboard or other material 4 mounted on the back 5 of the case a so

that, the said back with the cylinder, diaphragm and magnet system can be removed en bloc from the case.

Reinforcing strips are indicated at 6 and 5 are for example made of thin strips of cane. The case may be formed as a cylinder or be of any appropriate shape.

The drawing shows a construction in which the diaphragm is fixed all round its 10 edge to the cylinder 4 and whilst this form is generally preferable, it may be fixed at intervals, if desired, and any clamping or other fixed means, detachable or permanent, which will affect the natural period of vibration of the diaphragm to an extent similar 15 to that of clamping rigidly all round, may be employed.

The word conical herein employed includes modifications of a true cone in that, 20 for example the point may be flat or the sides may be or may contain flat parts so that in cross section the "cone" would not be a true circle.

What we claim is:

25 1. A loud speaker comprising a case, a cylindrical frame located within the case and secured at the inner edge thereto, and a conical diaphragm having a maximum di-

ameter corresponding to the diameter of the frame, the outer edge of the diaphragm 30 being secured to the outer edge of the frame and the apex of the diaphragm extending inwardly of the frame.

2. A loud speaker comprising a case, a cylindrical frame secured at one edge to the 35 case, a conical diaphragm having a maximum diameter corresponding to the diameter of the frame, the outer edge of the diaphragm being secured to the outer edge of the frame and the apex of the diaphragm extending inwardly of the frame, and ribs applied to the 40 surface of the diaphragm.

3. A loud speaker comprising a case, a cylindrical frame secured at one edge to the case, a conical diaphragm having a maximum diameter corresponding to the 45 diameter of the frame, the outer edge of the diaphragm being secured to the outer edge of the frame and the apex of the diaphragm extending inwardly of the frame, and ribs 50 on the respective inner and outer surfaces of the diaphragm.

In testimony whereof we affix our signatures.

ERIC VINCENT MACKINTOSH.
